UNITED STATES PATENT OFFICE.

FREDERICK A. ROBERTS, OF SOMERVILLE, MASSACHUSETTS.

BOLT-CLIPPER.

SPECIFICATION forming part of Letters Patent No. 769,357, dated September 6, 1904.

Application filed June 10, 1904. Serial No. 211,961. (No model.)

To all whom it may concern:

Be it known that I, FREDERICK A. ROBERTS, a citizen of the United States, residing in Somerville, in the county of Middlesex and State of Massachusetts, have invented certain new and useful Improvements in Bolt-Clippers, of which the following is a specification.

This invention relates to bolt-clippers, sometimes termed "bolt-cutters," such tools being used principally for clipping or cutting bolts, rivets, wires, rods, cables, and the like.

The invention relates to that portion of the device whereby the handles or levers and the cutting-jaws are adjusted from time to time as the cutters wear or for any other purpose and whereby when the tool is opened the adjusting-section is held securely, thus preventing relative movement and rattling.

The principal objects of my improved adjustment are to attain as high a degree of simplicity as possible and to lengthen the durability of the tool by reducing to a minimum the wear on the jaw and preventing digging into the jaw, a fault which has been much complained of by the users of adjusting mechanisms now in use in tools of this character.

The nature of the invention is fully described below and illustrated in the accompanying drawings, in which—

Figure 1 is a plan view of a bolt-clipper embodying my improved adjusting mechanism, a small portion being represented as broken out. Fig. 2 is an enlarged plan of the same with the outer portions of the handles or levers removed and one of the adjusting-sections shown in horizontal section. Dotted lines indicate the position of one of the jaws and adjusting-sections when the device has been adjusted by means of the cutters having become worn. In the first two figures the tool is represented with the jaw closed. Fig. 3 is a side view of the same. Fig. 4 is a section taken on line 4-4, Fig. 2. Fig. 5 is a plan view showing the jaws open.

Similar letters of reference indicate corresponding parts.

a a represent the operating handles or levers, pivoted together at their inner ends at *b*.

c c represent the cutting-jaws, provided at their outer ends with the cutters *d d*, said cut-

ting-jaws being connected by a lock-plate *e*, having holes *f*, which correspond in shape with the holes in gear-shaped nuts *g*, whereby said nuts are prevented from turning. These nuts are on bolts *h*, the said bolts, nuts, lock-plate, and cutting-jaws being constructed substantially in the ordinary manner.

Each of the handles or operating-levers *a* has its outer edge near the pivotal connection *b* cut away at *k* and *l*, as illustrated in Fig. 2. The recess formed at *k* is curved and substantially on the arc of a circle, and the recess formed at *l* is hook-shaped.

n n represent adjusting-sections, both being hollow and alike and each section being pivotally connected at its rear end by a suitable bolt or pivot *m* with the handle *a* on that side and at its forward end by a bolt or pivot *p* with the rear end of the jaw on the same side. Thus the adjusting-section *n* and jaw *c*, in connection with the pivots or bolts *h*, *p*, and *m*, constitute practically a toggle.

Each adjusting-section *n* is vertically bored to receive a bolt *q*, whose shank is flattened on its opposite sides, as shown in Fig. 2, and extends through the chamber or hollow portion in the adjusting-section *n*. This bolt fits in a correspondingly-shaped hole in the cam or eccentric *r*, located in the interior of the section, the periphery of said cam being adapted to fit in the recess *k* and the cam being between said recess *k* and the outer wall of the section *n*. This outer wall is provided with a horizontal hole *t*, through which there extends a strong hook *s*, the shank of which is screw-threaded to receive a suitable nut *u* and the inner or hooked end of which fits into the hook-shaped recess *l*. The cams *r* and hooks *s* in each section *n* are similar.

Fig. 2 represents in full lines a new tool closed before the cutters have become worn. The cams therefore have their broad sides swung outward toward the outer walls or edges of the adjusting-sections, while their narrowest portions lie in and bear against the sides of the recesses *k*. As the cutters become worn the bolts *q* are rotated, turning the cams, with the effect of swinging their broad portions toward and into the recesses *k*, thus forcing outward the adjusting-sections *n*.

(which swing on the pivots *m*) and also swinging outward the rear or inner ends of the jaw *c*, all as shown in dotted lines in Fig. 2, said dotted lines being illustrated in connection 5 with but one of the adjustments, although practically both jaws would be adjusted at the same time. The extreme limit of wear would be provided for when the broadest portions of the cams were swung into the recesses *k*— 10 in other words, when the cams were in exactly the reversed position from that indicated in full lines in Fig. 2. In whatever position the cams may be turned the handles are operated in exactly the same manner. The strong 15 hooks *s* serve to bind the handles or levers *a* and the adjusting-sections together, so that each adjusting-section is firmly secured to and moves with the corresponding handle. This 20 prevents all relative movement or rattling. Of course when adjustment is to be made the nuts *u* are loosened.

The bolts *p* and *q* are preferably connected by lock-plates *v*, similar to the lock-plates *e*, above described.

25 Having thus fully described my invention, what I claim, and desire to secure by Letters Patent, is—

1. In a bolt-clipper of the character described, the handles or operating-levers; the 30 cutting-jaws; the adjusting-sections *n* pivotally connected at their rear ends with the handles and at their forward or outer ends with the cutting-jaws; cams in the adjusting-sections adapted to bear against the handles; adjust- 35 able means for holding the said adjusting-sections in engagement with the corresponding handles; and means for operating said cams whereby the adjusting-sections can be swung outward or inward with relation to the forward 40 ends of the handles and thereby swing the cutters toward or from each other, for the purpose set forth.

2. In a bolt-clipper of the character de- 45 scribed, the handles or operating-levers; the cutting-jaws; the adjusting-sections *n* pivot-

ally connected at their rear ends with the handles, and at their forward or outer ends with the cutting-jaws; cams in the adjusting-sections adapted to bear against the handles; means for rotating said cams and thereby 50 swinging the forward ends of the sections outward or inward with relation to the forward ends of the handles; and adjustable hooks extending through the said adjusting-sections into engagement with the corresponding han- 55 dles, for the purpose set forth.

3. In a bolt-clipper of the character de- 60 scribed, the cutting-jaws; the handles or operating-levers *a* provided on their outer edges with the recesses *k*; the adjusting-sections *n* pivotally connected at their rear ends with the handles and at their outer ends with the cutting-jaws; the cams *r* in the adjusting-sections; the bolts *q* in the adjusting-sections, 65 said bolts rotating the cams against said recessed portions; and adjustable means for holding said adjusting-sections in engagement with the corresponding handles, for the purpose set forth.

4. In a bolt-clipper of the character de- 70 scribed, the cutting-jaws, the handles or operating-levers *a* provided on their outer edges with the hook-shaped recesses *l*; the adjusting-sections *n* pivotally connected at their rear ends to the handles and at their outer 75 ends to the cutting-jaws; cams supported by the adjusting-sections and adapted to bear against the handles *a*; means for operating said cams; and adjustable hooks *s* extending through the adjusting-sections into the said 80 hook-shaped recesses, for the purpose set forth.

In testimony whereof I have signed my name to this specification in the presence of two sub-scribing witnesses.

FREDERICK A. ROBERTS.
